UNITED STATES PATENT OFFICE.

MATHIAS HILLAS, OF NEW YORK, N. Y.

DESIGN FOR FUR JACKET.

Specification forming part of Design No. 7,647, dated August 18, 1874; application filed July 21, 1874.
[Term of Patent 7 years.]

To all whom it may concern:

Be it known that I, MATHIAS HILLAS, of New York, in the county of New York and State of New York, have invented a new and original Design for a Fur Jacket, of which the following is a specification:

Similar letters of reference indicate corresponding parts in both the figures.

This invention has for its object so to trim and embellish a ladies' fur jacket, by using thereon differently-colored fur, that it will appear as though the wearer carried a fur collar and a muff besides the jacket. The invention consists in trimming the upper and front part of the jacket with a fur having a different color from the body of the jacket, so as to constitute an imitation collar and muff on said jacket.

The letter A in the drawing represents a fur jacket, made of suitable size and shape, and having around its neck portion and along the front edges an imitation collar, B, formed on it of fur, while an imitation muff, C, is also formed in front of the jacket. The collar and muff are of a different color from the body of the jacket, though not made as separate articles of wearing apparel, as heretofore.

The design is thus ornamental, because it embellishes the jacket in a way in which ladies like to have it embellished, and is useful, because it enables one article to answer every purpose of three of ordinary design.

The imitation muff C is made to cover two pockets in the jacket, as indicated.

I claim as my invention—

The design for a fur jacket, having the imitation collar and muff, as shown.

MATHIAS HILLAS.
